[57] CLAIM

The ornamental design for a sanitary filtered candle blowing device, as shown and described.

DESCRIPTION

FIG. 1 is a left side elevational view of a sanitary filtered candle blowing device showing our new design, the person and cake shown in broken lines for illustrative purposes only;

FIG. 2 is a left side elevation view thereof, the right side elevation view being a mirror image;

FIG. 3 is a front elevational view thereof;

FIG. 4 is a rear elevational view thereof;

FIG. 5 is a top plan view thereof; and

FIG. 6 is a bottom plan view thereof.
